CONTAINER WITH RECLOSE AND SHIELD DEVICE

Arthur J. White, Hempstead, N. Y., assignor to
American Can Company, New York, N. Y., a
corporation of New Jersey

Application December 26, 1947, Serial No. 793,883

5 Claims. (Cl. 229—7)

1

The present invention relates to sheet metal containers or cans adapted to be opened by pressing a scored portion inwardly and has particular reference to such a container or can having means for shielding the raw edge of the opened portion and for reclosing the opened portion.

An object of the invention is the provision of a container or can wherein the raw edge left by pressing inwardly a scored portion of the can to provide a dispensing opening therein, is shielded to protect the consumer against injury when opening the can.

Another object is the provision of such a container or can wherein the raw edge shielding means has the additional function of serving as a reclosure element for the opened container or can.

Another object is the provision of such a container or can wherein the shield and reclosure may be made as a unitary structure which is economical and efficient and readily attached to a container or can.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a sealed can embodying the instant invention;

Fig. 2 is an enlarged fragmentary sectional view taken substantially along a plane indicated by the lines 2—2 in Fig. 1;

Fig. 3 is a view similar to Fig. 2 and showing certain of the parts of the can in a different position for dispensing the contents of the can;

Fig. 4 is a perspective view of the upper portion of a sealed can embodying a modified form of the invention;

Fig. 5 is an enlarged fragmentary sectional view taken substantially along a plane indicated by the lines 5—5 in Fig. 4;

Fig. 6 is a perspective view of the upper portion of a further modified form of the invention; and

Fig. 7 is an enlarged sectional view taken substantially along a plane indicated by the lines 7—7 in Fig. 6, with parts broken away, and with the movable part rotated into the position shown in dot and dash lines in Fig. 6.

As a preferred and exemplified embodiment of the instant invention Figs. 1, 2 and 3 of the drawings illustrate a conventional rectangular shaped can having rounded corners and used for hold-

2

ing condiments, granular substances or other dry materials including cocoa, dried milk, ground or bean coffee and the like. The can includes a fibre body 11 having a metal countersunk panel bottom 12 and a similar metal top 13 secured thereto in suitable end seams 14. The countersunk panel of the top member 13 is formed with a curved or semi-circular score line 15 which defines a curved or semi-circular depressible area 16 which is readily broken and bent downwardly and inwardly into the can by pressure of a thumb or finger of the consumer. When so depressed the area 16 breaks away along the score line 15 and bends along a line connecting the terminal ends of the curved score line, and thus forms a dispensing opening 17 for the contents of the can as best shown in Fig. 3.

Provision is made for protecting the consumer against injury from the raw curved edge which remains in the top 13 when the metal of the top is broken along the score line 15 during the opening of the can. For this purpose the top of the can is provided with an overcap 21 made of fibre or other suitable, preferably soft material. This overcap functions as a shield 21 which lies flat against the sheet metal top 13 on its outer surface. This shield preferably is the same shape as the top of the can and just large enough to fit within its sunken panel. Along the straight portions of the top, the top end seam 14 may be crimped inwardly to form retaining lugs 22 which project over the edges of the shield as shown in Figs. 2 and 3 and retain the shield or overcap against displacement.

Above the depressible scored area 16 in the top 13, the shield 21 is cut through along a curved line of severance 24 which is adjacent but spaced inwardly from the score line 15 in the top member, so that an overlapping ledge 25 of the shield 40 projects over and thus shields the sharply severed edge. The ends of the curved line of severance 24 in the shield preferably terminate adjacent the terminal ends of the score line 15, and are connected by a straight crease line 26 which together with the line of severance 24 define a reclosure flap or member 27 which is hingeable upwardly along the crease line. The crease line 26 thus constitutes a hinge for the reclosure member. A lifting tab 31 secured by a wire staple 32 to the reclosure member 27 may be provided for easy lifting or hinging of the reclosure member into an open position as best shown in Fig. 3.

Thus when it is desired to open the can, the reclosure flap 27 is first raised or hinged into an

open position by pulling on the lifting tab 31 as shown in Fig. 3. This provides an opening in the shield which exposes the depressible area 16 in the can top member 13 so that this area may be broken inwardly to provide the dispensing opening 17. Since the score line 15 is disposed or hidden under the ledge 25 of the shield 21 beyond the defining line of severance 24 of the reclosure flap 27, the sharp raw edge which results from the breaking of the score line is out of reach and the fingers of the consumer are thereby protected against injury therefrom. After a partial dispensing of the contents of the container by spoon or other tool, or by pouring, the reclosure flap 27 may be returned to its normal closed position in the shield opening as shown in Figs. 1 and 2 and thereby reclose the container for storage.

In some cases it may be desirable to omit the reclosure flap 27 from the shield. In such cases the shield may be made shorter, as indicated by the dot and dash line 35, and slideable along the top of the can. Such a shorter shield would be provided with an opening, which is movable into and out of register with the dispensing opening 17, the effective registrable opening of the shield being smaller than the dispensing opening of the inner top in order to shield the raw edge of the dispensing opening.

In the modified form of the invention as shown in Figs. 4 and 5, the shield 21 is applied to a round can comprising a sheet metal body 41 having a sheet metal countersunk top 42 permanently attached thereto by a suitable interfolded end seam 44. As in the preferred form of the invention, the top member 42 of the round can is formed with a curved or semi-circular score line 45 which defines a depressible area 46 which is breakable or bendable downwardly and inwardly into the can to provide a dispensing opening.

In this round can, the shield 21 with its protecting ledge 25 and hingeable reclosure flap 27, is circular in shape to fit the can and is disposed in the countersunk panel of the top 42 as in the preferred embodiment. The shield is retained in place by a plurality of inwardly bent lug portions 48 of the top end seam 44, which project over the peripheral edge of the shield.

In order to prevent rotation of the shield 21 relative to the can top 42, the can top is formed with a locating bead or projection 49 which is struck outwardly from the can top at a place opposite to the depressible area 46 and which extends up into a locating aperture 51 formed in the shield. The engagement of the bead 49 in the aperture 51 maintains the reclosure flap 27 of the shield in proper register with the depressible area 46 in the can top 42.

As in the preferred form of the invention, the reclosure element 27 of the modified form of the shield 21 is raised to expose the depressible area 46 in the can top 42 so that this area may be forced inwardly to provide a dispensing opening for the can. In this modified form also the score line 45 is covered by the ledge 25 of the shield and thus the sharp raw edge which results from the breaking of the score line is out of reach and the hand of the consumer is thereby protected against injury therefrom. In this can the reclosure flap 27 may be returned to its original closed position for reclosing the can for storage.

A further modified form of the invention as shown in Figs. 6 and 7 discloses a can similar to that shown in Figs. 4 and 5 and having a shield

or overcap 55 which is provided with an opening 56 of similar contour to that of the depressible area 46 in the can top, but of slightly smaller dimensions. There is no reclosure flap on this shield. The shield lies flat against the can top and is rotatable thereon to move the opening 56 into and out of register with the depressible area 46. The end seam of the can is curled inwardly over the shield to retain it in place. Since the effective registrable opening in the shield is slightly smaller than the depressible area 46, the shield thus overlaps the score line 45 when the opening 56 in the shield is in register with the depressible area and hence the raw edge left by the breaking of the score line when the depressible area is forced inwardly, is covered to guard against inflicting injury on the consumer.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container having in a metallic wall section thereof a score line setting off a depressible area bendable inwardly to produce a dispensing opening for the container, a shield disposed over said metallic wall section and having an opening opposite to and smaller than said depressible area, the material of said shield projecting over said score line for shielding the raw cutting edge of the metal resulting from the breaking of said score line when said depressible area is bent inwardly to produce said dispensing opening, and a reclosure element in said shield for reclosing the dispensing opening in said container.

2. A container having in a metallic wall section thereof a score line setting off a depressible area bendable inwardly to produce a dispensing opening for the container, a movable shield disposed over said metallic wall section and having an opening therein registrable with said depressible area, the effective registrable opening in the shield being smaller than the depressible area in the metallic wall section of said container leaving a projecting portion for shielding the raw edge of the metal resulting from the breaking of said score line when said depressible area is bent inwardly to produce said dispensing opening, and a reclosure element embodied in said shield for reclosing the dispensing opening in said container.

3. A container having a metallic wall section in which a score line sets off a depressible area bendable inwardly to break said wall along said score line, a shield disposed in protecting relation over said wall section, said shield being provided with an aperture smaller than and aligned with said depressible area with a portion of said shield adjacent the edge of said aperture extending over said score line and said depressible area to serve as a guard against injury of the consumer by contact with the raw edge of an opening made in said metallic wall section when said score line is broken by pressure applied to said depressible area.

4. A container having a body, a metallic end member secured to said body in an end seam, a score line cut in said end member and setting off a depressible area, said depressible area being engageable by a finger of the user and under pres-

sure being bendable inwardly along an unscored line of bend to produce a dispensing opening in the container end member, and a shield in contact with said metallic end member, said shield having an opening smaller than said depressible area and located directly over the same, the periphery of said shield opening projecting inwardly beyond said score line in said end member and closely shielding the raw cutting edge of the metal resulting from the breaking of said score line when said depressible area is bent inwardly in the forming of said dispensing opening.

5. A container having a score line setting off a depressible area in a metallic wall section thereof, said depressible area being engageable by a finger of the user and under pressure being bendable inwardly along an unscored line of bend to produce a dispensing opening for the container, and a shield movably held in contact with said wall section, said shield having an opening registerable with said depressible area, the effective

10

5 opening of said shield when so registered being smaller than said depressible area leaving a projecting portion of the shield for shielding the raw cutting edge of the metal resulting from the breaking of said score line when said depressible area is bent inwardly in the production of said dispensing opening.
